SAFETY CONTROL FOR GASEOUS FUEL BURNERS

Paul L. Betz, Baltimore, Md., assignor to Consolidated Gas Electric Light and Power Company of Baltimore, Baltimore, Md., a corporation of Maryland

Application May 14, 1946, Serial No. 669,473

8 Claims. (Cl. 236—21)

1

2

This invention relates to safety controls for burners of gaseous fuels, and has particular utility when applied to such controls for automatic water heaters and the like, although it is not limited thereto.

In safety controls of the type referred to it is common practice to use, in addition to a thermostatically operated valve for controlling the flow of fuel to the main burner, a valve for determining fuel flow that is under the control of an electromagnet in a circuit including a generator of thermoelectric current subjected to the heat of a pilot burner, so that upon failure of the pilot for any reason the last referred to valve is closed and discontinues further flow of fuel.

When it is desired to reset the control after closure of the valve that is under the control of the thermoelectric current, the flow of fuel should be to the pilot burner only until the safety control has been reconditioned by reestablishment of the pilot flame, as otherwise gas may issue from the main burner, causing a dangerous condition. Fuel controlling devices have been proposed to permit the manual opening of the pilot burner fuel passage following which the opening of the fuel passage to the main burner is permitted only after the pilot burner has been lighted and the safety control has been reconditioned for safe operation. Devices for this purpose have included a manually operable main valve which directs the flow of gas only to the pilot burner during the starting operation and then, upon proper conditioning of the associated safety control, this manually operated main valve may be advanced to the "on" position whereupon the supply of gas to the main burner and to the pilot burner is shifted to the outlet side of the safety shutoff device. Movement of the said manually operable main valve prior to reaching the "on" position can be accomplished only when the thermostat control lever is in the position for closing the thermostatic valve that determines the flow of fuel to the main burner, this being effected by the use of interlocking means between the thermostat and the main valve. Upon reaching the "on" position, however, the interlocking means may be adjusted to the desired water temperature setting, thereby opening the thermostatically controlled valve in the main burner supply passage.

Another device for accomplishing this purpose is disclosed in U. S. Patent No. 2,361,945 to W. F. Jackson in which the resetting means controls directly a valve in the pilot burner passage, effects the closure of the thermostatically operated valve,

and also conditions the safety shutoff device to its operative position.

These devices may thus be characterized as providing separate valves for controlling the pilot gas passage during the resetting operation.

It is an object of this invention to provide an improved safety control which makes unnecessary the use of a separate pilot control valve for use during the resetting operation.

10 Another object of this invention is to provide an improved safety control wherein, by operation of a single member, the closure of the thermostatically operated valve is assured before the safety shutoff valve is opened and wherein fuel is readmitted to the main burner only after the safety control has been reconditioned for future safe operation.

Another object of this invention is to provide a safety control of improved construction that 20 is foolproof in its operation and automatically assures that no fuel can escape from the main burner until the pilot has been relighted and the safety control has been reconditioned for safe operation.

25 Another object of this invention is to provide an improved device of the type characterized which is simple in construction, composed of parts that are readily manufactured and assembled, and certain in operation.

30 Other objects will appear as the description of the invention proceeds.

The invention is capable of receiving a variety of mechanical expressions only one of which is illustrated on the accompanying drawing, and it is to be expressly understood that the drawing is for purposes of illustration only, and is not to be construed as a definition of the limits of the invention, reference being had to the appended claims for that purpose.

40 The single figure of the drawing is a vertical elevation, largely in section, of a safety control embodying the present invention.

In the form shown, a casing 10 of any suitable size, construction and material, and illustrated as formed in one piece, is provided with a threaded nipple 11 for attachment to any suitable source of gaseous fuel, a threaded nipple 12 for attachment to any suitable main burner and a threaded nipple 13 for attachment to any suitable pilot burner. Internally, the casing is suitably subdivided so as to provide three chambers, a chamber 14 in communication with the nipple 11, a chamber 15 in communication with the nipple 12 and a chamber 16 in communication with the nipple 13 and also forming a means of communication

between the chambers 14 and 15 under operating conditions.

The safety shutoff device is mounted in the chamber 14 and controls communication between the chambers 14 and 16. To this end a valve seat member 11 of any suitable construction, here shown as a ring threadedly engaged in the aperture 18, is provided with a valve seat 19 surrounding the valve port 20. Mounted for cooperation with said valve seat 19 is a valve member 21 of any suitable construction carried by a valve stem 22, the connection between valve member 21 and its stem 22 preferably being such as to permit slight relative movement between the parts so as to assure perfect sealing when valve member 21 engages its seat 19.

Valve stem 22 extends through an aperture 23 in a housing member 24 carried by a bonnet 25, as by frictional fit, spot welding or the like, threadedly mounted at 26 at the outer extremity of the chamber 14. Interiorly of said housing member 24 valve stem 22 is provided with an electromagnet armature member 27 which is also preferably mounted on the valve stem 22 so as to permit relatively free motion therebetween. Projecting into adjacency with armature member 27 is a U-shaped electromagnet core 28 carried by the bonnet 25 in any suitable way and having on its legs electromagnet windings 29 adapted to be energized from any suitable source, such as a thermocouple appropriately positioned so as to be heated by the flame of the pilot burner. When energized the electromagnet coil 28 provides sufficient attractive force to hold the armature 27 in engagement with pole faces 28a of core 28.

Electrical connection with the electromagnet winding 28 may be effected in any suitable way as by a connector in the form of a central conductor 30 suitably insulated from the surrounding metallic parts as by an insulating tube 31, insulating washer 32 and an insulating cup 33. The inner end of conductor 30 is connected at 34 to one end of the winding 28, while the outer end of said conductor terminates in a contact disk 35, insulated from the surrounding metallic parts by the insulating cup 33. The opposite end of the winding 28 is grounded to the bonnet member 25 as shown at 36. By inserting a suitable contact member into the socket 37 to effect electrical engagement with the disk 35 and grounded bonnet 25 the thermocouple referred to is electrically connected to the electromagnet winding 28.

Valve stem 22 projects beyond the face of valve member 21 as shown at 38 and it is provided with an interior chamber 39 having at its outer end an annular plug 40 held therein in any suitable way. Projecting through the aperture in said plug 40 is an operating member in the form of a finger 41 having a head 42 that is normally held against the plug 40 by a coil spring 43 mounted in the chamber 39. Interposed between the valve member 21 and the bottom of the housing member 24 is a second coil spring 44 whose force constant is materially less than the force constant of spring 43 so that when a force is applied to finger 41 to raise valve member 21, spring 44 is readily compressed while spring 43 has negligible compression.

The thermostatically operated valve mechanism is associated with the chamber 15, and to this end a valve seat member 45 of any suitable construction, here shown as a disk threaded into aperture 46, is provided with a valve seat 47 and

one or more apertures 48 to permit flow of fuel from the chamber 16 to the chamber 15 when the valve member next to be described is in open position. Mounted for cooperation with the valve seat 47 is a valve member 49 of any suitable construction provided with a valve stem 50 projecting from the valve member. Valve stem 50 projects through a centrally arranged guide opening 52 in the valve seat member 45 and is provided with two interior chambers 53 and 103 with a partition wall 104 therebetween. Annular plug 54 is held in the outer end of chamber 53 in any suitable manner. Mounted within chamber 53 is a pin 55 having a head 56 between which and the end of the chamber 53 reacts a coil spring 57. Also attached to the valve stem 50, and here shown as made in one piece with the plug 54, is a spring seat 58 between which and the valve seat member 45 reacts a coil spring 59. At the other end of valve stem 50, chamber 103 is provided with an annular plug 105 which is held in position at the outer end of chamber 103 in any suitable manner. Mounted within chamber 103 is a pin 106 having a head 107 between which and the end of chamber 103 reacts a coil spring 108.

The force constant of spring 57 is materially greater than that of the spring 59, and the force constant of spring 108 is materially greater than that of spring 57. Under normal operating conditions when a force is applied to the outwardly projecting extremity 60 of the pin 55, spring 59 is readily compressed while spring 57 has only a negligible compression. However, if valve member 49 is in its open position and a force is applied to finger 106 in a direction for closing the valve member 49, spring 57 can be compressed by movement of pin 55 into the chamber 53, and with negligible compression of spring 108. Valve member 49 may thus be engaged with its seat 47 notwithstanding that the projecting end 60 of the pin 55 is held against upward movement, as viewed in the drawing, by the thermostat herein-described.

The outwardly projecting end 60 of pin 55 engages a diaphragm 61 held in position in any suitable way as by a pair of retaining rings 62 and 63 threaded at 64 into the bore of the chamber and thereby providing a gastight closure with the chamber 15. Diaphragm 61 is designed to be operated by any suitable thermostat mechanism associated therewith. In the form shown the thermostat is of the snap acting type and includes a clicker disk 65 carrying a post 66 adapted to engage and deflect the diaphragm 61. Clicker disk 65 is supported on a seat 67 provided on the retaining ring 62. Engaging said clicker disk 65 is a disk-shaped member 68 having an annular seat 69 for cooperation with the clicker disk 65 and of smaller diameter than the seat 67. Disk shaped member 68 is actuated by a thermostat of any suitable construction, here shown as a known type of rod and tube thermostat of the bimetallic type comprising a rod 69 composed of a metal having a low coefficient of expansion, such as a nickel steel containing approximately 36% nickel and 0.2% carbon, and an outer tubular member 70 of high coefficient of expansion, such as copper. The outer end of rod 69 is threadedly connected at 71 to a plug 72 which in turn is suitably connected to the outer end of tubular member 70. The inner end of tubular member 70 is secured in position in any suitable way as by being threaded at 73 into an aperture in the casing 10. The inner end 74 of rod 69 is seated on the disk shaped member 68, and for

adjustment of the thermostat in a manner well understood in the art said rod 69 may be provided with a collar 75 located in a chamber 76 formed in the casing 10 and having an arm (not shown) extending exteriorly of the casing 10 so that by rotation of the arm and collar 75 the rod 69 may be adjusted with respect to the sleeve 70 to predetermine the temperature at which the thermostat actuates the clicker disk 65.

While one particular thermostat and snap actuating mechanism operated thereby have been described with considerable particularity, it is to be expressly understood that the invention is not limited to the mechanism illustrated and described, as any suitable thermostat and any suitable mechanism operated thereby for actuating the thermostatically controlled valve member 49 may be used.

Casing 10 is normally mounted in association with a water tank or comparable means with the thermostat projecting into heat interchanging relationship with the controlling medium. To this end the casing 10 is shown as provided with an elongated collar or boss 77 threaded at 78 for reception in a threaded aperture in the tank or the like so that the thermostat 69, 70 is subjected to the temperature of the water or other medium in said tank.

Chamber 16 is provided with any suitable means for actuating the fingers 41 and 106 and thereby the valve members 21 and 49 in proper sequence. For purposes of illustration a cylindrical cam arrangement has been shown comprising a rod 79 provided with a tapered cam 80 circular in cross section for cooperation with finger 41 and a second tapered cam 81 circular in cross section for cooperation with the finger 106. The position of the parts shown in the drawing corresponds to the normal operating position of rod 79, cam member 81 being in position to engage finger 106 upon slight inward movement of rod 79 to the left as viewed in the drawing, while cam member 80 is positioned to engage the finger 41 only after an appreciable inward movement of said rod 79, to the end that finger 41 will be operated to open the valve member 21 only after cam member 81 has engaged finger 106 and seated valve member 49 against its seat 47.

Cam member 80 is also provided with a valve face 82 adapted to cooperate with a seat 83, here shown as carried by a plug 84 threadedly received in the opening 85 and provided with an aperture 86 through which projects the rod 79 to the exterior of the casing 10 where it is provided with a push button 87. Valve seat 83 surrounds the aperture 86 so that when the valve face 82 of cam member 80 is in engagement with said seat 83 leakage through the aperture 86 is prevented.

The opposite end of rod 79 is telescopically received within and rigidly fixed to a sleeve 88 which is mounted for telescopic movement within the aperture 89 of the nipple leading to the pilot burner. Sleeve 88 may be attached to rod 79 in any suitable way as by brazing. Sleeve 88 is provided with suitable apertures 90 so that fuel may flow from the chamber 16 to the interior bore 91 thereof and thence out through the nipple 13. Surrounding sleeve 88 and reacting between the wall of the casing 10 and a spring retaining member 92 is a coil spring 93 which normally urges the rod 79 to the right as viewed in the drawing. Sleeve 88 is designed to fit the

bore of passage 88 accurately and, in conjunction with the cooperation between rod 79 and aperture 86, effects the proper alignment of the rod 79 with the cam members carried thereby.

5 The position of the valve member 21 as shown in the drawing corresponds to that existing after the pilot burner has failed so that the thermoelectric current flowing through the coil 29 is incapable of holding the armature 27 against the pole pieces 28a of the electromagnet core 28 whereby, under the action of the spring 44, the valve member 21 has been moved to engage the seat 47 and thereby discontinue the flow of fuel through the casing 10. It will be observed that 10 in this position of parts no fuel can flow through either of nipples 12 or 13 even though the thermostat is holding the valve member 49 in its wide open position because the water or other controlling medium is cold.

15 To reset the device, the rod 79 is moved to the left as viewed in the drawing by manually pressing on button 87. Such movement to the left first causes the inclined surface of cam 81 to engage finger 106 and move the valve member 21 20 into engagement with its seat 47 so that, when fuel is admitted to the chamber 16, it cannot flow outwardly through the chamber 16 and nipple 12. If as illustrated the thermostat is then holding the valve member 49 in its open position, said 25 valve member is none the less closed by the foregoing movement because pin 55 can move into chamber 53 against the force of spring 57 as the cam 81 moves the valve member 49 into engagement with its seat.

30 Further movement of rod 79 toward the left as viewed in the drawing and after valve member 49 engages its seat 47 is accompanied by movement of finger 106 into chamber 103 and the compression of spring 108. Upon said further movement of rod 79 to the left and following the engagement of valve member 49 with its seat 47, the inclined surface of the cam 80 engages the finger 41 causing the valve member 21 to be raised from its seat, against the force of spring 44, until the armature member 27 is engaged with the pole faces 28a of the core 28. If after such engagement cam member 80 still tends to move finger 41 upwardly as viewed in the drawing the latter may move into the chamber 39 against the force of the spring 43 even though the valve member 21 cannot continue to move upwardly, as viewed in the drawing, because of the engagement of armature member 27 with the ends of the U-shaped core 28. Thereby rod 79 can be moved to its extreme lefthand position without injury to the parts after assuring that armature member 27 is positively engaged with the core of the electromagnet.

35 50 While push button 87 is thus held in its innermost position fuel may flow from the chamber 16 through the apertures 90 into the passages 91 and 89 and thence to the pilot burner. The pilot may thereupon be lighted, energizing the thermocouple and therefore reenergizing the electromagnet coil 29 to retain the armature member 27 against the pole faces, so that valve member 21 is held in its open position after rod 79 is released and moved to its right-hand position by the action of spring 93. Fuel is thus permitted to flow from the chamber 16 into the chamber 16 and, upon release of the rod 79, valve member 49 returns to its open position under the action of the spring 57. Thus the fuel may flow 55 both to the main burner through the nipple 12

under the control of the thermostatic valve member 49 and to the pilot burner through the nipple 13. If the rod 19 should be released before the pilot burner has become effective to reenergize the electromagnet coil 29 so as to hold the valve member 21 in open position, valve member 21 will be moved to closed position under the action of its spring 44, again shutting off the flow of fuel to the thermostatically operated valve mechanism as well as to the pilot burner, so that fuel can be readmitted to the pilot burner only after the thermostatic valve member is again closed. Thus fuel may flow both through the thermostatically operated valve mechanism and to the pilot burner only after the pilot has been re-ignited and the electromagnet coil 29 has been reenergized sufficiently to hold the valve member 21 in its open position. Once the control has been properly reconditioned, however, the control of the valve member 49 is solely from the thermostatic mechanism which opens and closes said valve as required by the temperature of the medium to which the thermostat is subjected.

It will therefore be perceived that the present invention provides a simple, efficient and fool-proof device which assures that fuel cannot flow to the main burner until the pilot has been re-ignited and the safety control has been properly reconditioned for future safe operation. As soon as the pilot fails, flow of fuel through the casing, both to the main burner and the pilot burner is discontinued, and flow of fuel to the main burner may thereafter be reestablished only after the pilot has been re-ignited and the safety shutoff mechanism has been properly reconditioned for safe operation. All of this is effected by manipulation of a single member thereby avoiding the use of a separate valve for controlling the pilot gas passage during the resetting operation.

While the embodiment of the invention illustrated on the drawing has been described with considerable particularity it is to be expressly understood that the invention is not limited thereto as the same may receive a variety of mechanical expressions, some of which will now be apparent to those skilled in the art, while changes may be made in the details of construction, arrangement, sizes, proportion of parts, etc., without departing from the present invention. While one form of thermostat and one form of clicker disk type of snap actuating mechanism has been illustrated and described, it is to be expressly understood that the invention is not limited thereto as any suitable thermostat and operating mechanism for a thermostatically controlled valve may be used. Also, any suitable form of electromagnet and source of thermoelectric current may be employed. Reference is therefore to be had to the appended claims for a definition of the invention.

What is claimed is:

1. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connecting for

8
closing said first named valve, a member operatively connected to said second valve for opening the same and restoring controlling relationship with said thermoelectrically actuated device, and a manually operated device cooperating with said members for operating the same in sequence and enforcing closure of said first valve if open before opening said second valve.

2. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, said operative connections including yieldable means to enable closure of said first named valve when it is being held open by said thermostat, a member operatively connected to said second valve for opening the same and restoring controlling relationship with said thermoelectrically actuated device, and a manually operated device cooperating with said members for operating the same in sequence and enforcing closure of said first valve if open before opening said second valve.

3. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, a member operatively connected to said second valve for opening the same and restoring controlling relationship with said thermoelectrically actuated device, yieldable means interposed between said last named member and said second valve to enable movement of said member after said second valve is stopped by said thermoelectrically actuated device, and a manually operated device cooperating with said members for operating the same in sequence and enforcing closure of said first valve if open before opening said second valve.

4. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, yieldable means

interposed between said member and said first named valve to enable movement of said member after said first named valve is closed, a member operatively connected to said second valve for opening the same and restoring controlling relationship with said thermoelectrically actuated device, and a manually operated device cooperating with said members for operating the same in sequence and enforcing closure of said first valve if open before opening said second valve.

5. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, a member operatively connected to said second valve for opening the same and restoring controlling relationship with said thermoelectrically actuated device, and a manually operated device cooperating with said members for operating the same in sequence and enforcing closure for said first valve if open before opening said second valve, said manually operated device including a single member provided with means for engaging and operating said members.

6. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, a member operatively connected to said second valve for opening the same and restoring controlling relationship with said thermoelectrically actuated device, and a manually operated device cooperating with said members for operating the same in sequence and enforcing closure of said first valve if open before opening said second valve, said manually operated device including a reciprocating rod provided with cams for engaging and operating said members.

7. In a safety control for burners of gaseous fuels of the type including a fuel passage for a main burner, a second fuel passage for supplying fuel to said first named passage and to a pilot burner passage, a valve for controlling fuel flow through said first named passage, a thermostat

having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, a member operatively connected to said second valve for opening the same and restoring controlling relationship with said thermoelectrically actuated device, a manually operated device cooperating with said member for operating the same in sequence and enforcing closure of said first valve if open before opening said second valve, said manually operated device including a single member provided with means for engaging and operating said members, and resilient means cooperating with said single member for normally holding the means thereon out of operative engagement with said first named members.

8. In a safety control for burners of gaseous fuels of the type including a fuel passage for a main burner, a second fuel passage for supplying fuel to said first named passage and to a pilot burner passage, a valve for controlling fuel flow through said first named passage, a thermostat having operative connections to said valve, a second valve for discontinuing fuel flow through said second passage and a thermoelectrically actuated device for controlling said second valve, a resetting means for said second valve including the combination of a member operatively connected to said first named valve and separate from said first named operative connections for closing said first named valve, a member operatively connected to said second valve for opening the same and restoring controlling relationship with said thermoelectrically actuated device, a manually operated device cooperating with said members for operating the same in sequence and enforcing closure of said first valve if open before opening said second valve, said manually operated device including a single member provided with means for engaging and operating said members, resilient means cooperating with said single member for normally holding the means thereon out of operative engagement with said first named members, and valve mechanism operable by said single member for preventing leakage of fuel around said manually operated device and normally held close by said resilient means.
